CONDUIT VALVE FOR PAPER PULP LINES
AND THE LIKEJoseph Belanger and Ernest Durnin,
Escanaba, Mich.

Application November 23, 1931, Serial No. 576,930

3 Claims. (Cl. 137—139)

Our invention relates to improvements in conduit systems for paper pulp and the like and has particular reference to a novel valve means for controlling the flow of the pulp in its passage 5 from one treatment tank, or instrumentality to another.

In paper mills the pulp conduit system necessarily includes a number of valves for controlling the flow of pulp. For instance, in the case of 10 the stock or pulp line leading from the stock tank above the battery of beaters is provided with a separate branch leading down to the respective beaters and, intermediate the ends of such branches are placed gate valves for controlling the 15 supply of pulp to a particular beater. The use of gate valves, and particularly intermediate the ends of the branch lines as aforesaid, is very objectionable. In the first place the portion of the 20 branch line between the valve and the stock line serves as a pocket for catching and receiving the pulp when the valve is closed. Not only this, but the pitch and other matter in the pulp very 25 soon gums up the gate valves or plug valves to such an extent that they cannot be operated,—it being common knowledge that such valves must 30 be cleaned approximately every forty-eight hours. Inasmuch as most mills have four or five stock lines disposed over the beaters so that stocks of various character can be fed thereto, or mixtures of several different stocks,—the matter of 35 economy in space above the beaters becomes an important item. The gate valves take up considerable lateral space and reduce considerably the 40 number of stock lines that can be accommodated above a given beater. Furthermore, the location of the gate valves intermediate the ends 45 of the branches leading from the stock lines to the beater constitute an additional fitting over and above the T-fitting whereby the branch line 50 is connected to the stock line.

It is, therefore, the primary object of our invention to overcome the objections aforementioned and to provide in a paper pulp conduit system or the like, a novel valve which may be incorporated 45 in the stock line, for instance, in lieu of a T-fitting for supporting the branch lines which lead to the beaters,—thus saving the expense of a special valve fitting and effecting a great economy of lateral space above the beaters so that the 50 maximum number of stock lines may be employed without crowding.

More specifically, it is an object of the invention to provide a novel valve for the purpose specified which will be automatically cleaned by the 55 passage of the pulp through the conduit and

which will not in any way impede the flow of pulp.

A further object of the invention is to provide 5 a valve as characterized, incorporating a novel operating means which is susceptible of relative adjustment with respect to the valve casing,—the invention contemplating in addition a valve susceptible of both manual and mechanical operation.

The invention also resides in certain novel 10 features of construction, combination and arrangement of the various parts and in certain modes of operation as will be readily apparent to those skilled in the art upon reference to the accompanying drawing in connection with the 15 detailed descriptive matter appearing hereinafter.

It is to be understood that the disclosures herein 20 depict what are now regarded as preferred forms of the invention. However, it will be obvious that various changes and modifications 25 may be made without departing from the spirit and scope of the subject matter claimed hereinafter.

In the drawing, wherein the same reference 25 characters have been used to designate the same parts in all views,

Figure 1 is a vertical sectional view taken 30 through a valve casing and illustrating our invention in the phase which contemplates hydraulic or pneumatic operating means, and

Figure 2 is an elevational view illustrating the 35 application of the invention to the stock line and branch which supplies the paper pulp to the beater.

Referring specifically to the drawing, numeral 40 5 denotes the valve casing which, as will be observed, has the form of a T-coupling having end flanged outlets 6, a bottom flanged outlet 7, but which has a top neck or outlet 8 provided with the disk or closure 9 which may be bolted or clamped to such neck or outlet 8 in the usual or in any preferred manner.

The closure plate 9 is provided with a medial bearing 9a carrying the packing gland assembly 45 10, providing a guide and seal for the valve stem 11, carrying at its lower end the disk-like head 12, which is provided with a medial recess at its rear face for receiving the headed end 11a of the valve stem upon which is superposed the washer 13. The clamp nut, or bushing, 12a is threaded 50 in the recess of valve 12 and securely holds the valve and stem assembled.

Figure 1 discloses very clearly the novel insert, or liner, bushing 14 which is adapted to be inserted into the bottom outlet 7 of the valve casing 55 6. In this connection it is noted that the upper

end of the liner bushing 14 provides the seat 14a for the valve 12,—such seat extending below the plane of the conduits 6, 6, through the valve body 5.

5 Especial attention is directed to the formation of the valve or head 12,—it being noted that its upper surface is fusto-conical and slopes very gradually in the direction of the periphery of the valve head. Thus, the pulp flowing through the stock line A (Figure 2) will serve to effectually clean the valve head 12, which forms no obstruction to the passage of the pulp. Obviously, the seat will not be clogged.

10 The closure plate which rests upon the periphery of the upper outlet or neck 8 also serves as a support for what might be termed a bonnet 15,—such bonnet 15 having a flanged base portion 16 establishing means for the reception of bolts or machine screws which are availed of for clamping the bonnet to the closure plate 9 and the latter to the periphery of the neck 8.

15 Figure 1 also very clearly illustrates that the upper end of the bonnet or support 15 is provided with the annulus guide 17, whose diameter is less than the major diameter of the bonnet or support 15 and serves as a keeper or guide within which the cylinder 18 is adjustably supported. Set screws 17a are preferably used for maintaining the cylinder 18 in a desired relative 20 adjustment with respect to the guide member 17.

25 Within the cylinder 18 works the double acting piston 19 comprehending the oppositely directed leather cups, and other conventional features of construction, which are clamped against the shouldered end 11b of the valve stem 11 by means of the nut 20. Springs 18a and 18b assist in operation of piston 19.

30 The upper end of the cylinder 18 is closed by the cap 21, which has the tapped inlet 22 which is adapted to receive the pressure fluid conduit or pipe 22a.

35 The lower end of the cylinder 18 is provided with a closure cap 23 which is threaded thereon and has the medial bearing 23a which with the packing gland nut 25 and filler provides a seal and 40 guide for the stem,—preventing as will be obvious, the escape of the pressure fluid from the cylinder 18. The closure 23 has the fluid inlet 24 for the pressure fluid line 24a.

45 Having thus described our invention, what we claim as new and desire to secure by Letters Patent is:

50 1. In a valve comprising a body having a pair of horizontally aligning openings providing a main line passage therethrough and a pair of vertically aligning openings, a valve insertible through one of said vertically aligning openings, a seat provided in said other vertical opening below the plane of said horizontally aligning openings for seating said valve, said valve when located on said seat having substantially its entire rear face projecting into said main line passage whereby to avoid the creation of a material-catching pocket adjacent said valve seat, said rear

5 face of said valve being beveled to reduced thickness in the direction of its edge whereby to present a substantially non-obstructing surface to material passing through said main line passage and to deflect such material away from the valve seat, a stem carried by said valve, a closure for said other vertically aligning opening and providing a guide for said valve stem, an operating carrier cylinder for said valve stem and co-axial therewith, said carrier providing a guide cooperating with said first-named guide for aligning the valve with its seat, a support having a concentric guide portion for said carrier spaced above said closure and a shoulder at the inner end of said guide portion, said support being removably carried by said closure and telescopically receiving said carrier, means for securing said carrier and support together in predetermined adjusted positions, and the valve stem guide of said operating cylinder having a stop portion cooperating with said shoulder of said support whereby to limit movement of said carrier away from said closure.

55 2. In a valve comprising a body having a pair of horizontally aligning openings providing a main line passage therethrough and a pair of vertically aligning openings, a valve insertible through one of said vertically aligning openings, a seat provided in said other vertical opening, a stem carried by said valve, a closure for said vertically aligning opening and providing a guide 10 for said valve stem, an operating carrier cylinder for said valve stem and co-axial therewith, said carrier providing a guide cooperating with said first-named guide for aligning the valve with its seat, a support having a concentric guide portion 15 spaced above said closure and a shoulder at the inner end of said guide portion, said support being removably carried by said closure and telescopically receiving said carrier, means for securing said carrier and support together in predetermined adjusted positions, and the valve stem guide of said operating cylinder 20 having a stop portion cooperating with said shoulder of said support whereby to limit movement of said carrier away from said closure.

25 3. In a valve construction including a casing providing a valve seat, a valve stem having a head adjacent one end, an operating member secured to said stem adjacent the other end, a cylinder surrounding said operating member and within which said stem and operating member are adapted to slide, said cylinder providing separate 30 guide portions for said operating member and stem, a support having a constructed portion spaced above said casing and providing a shoulder, said restricted portion of said support telescopically receiving said carrier, and said stem guide portion of said casing having a shoulder adapted to engage said first-named shoulder to 35 limit outward movement of said cylinder and valve.
